UNITED STATES PATENT OFFICE.

REINHART SPENGLER, OF NEW YORK, N. Y.

MACHINE FOR MAKING PAPER TUBES.

SPECIFICATION forming part of Letters Patent No. 507,764, dated October 31, 1893.

Application filed February 9, 1891. Serial No. 380,766. (No model.)

To all whom it may concern:

Be it known that I, REINHART SPENGLER, of New York, in the county and State of New York, have invented a certain new and useful Improvement in Machines for Making Paper Tubes, of which the following is a specification.

Paper tubes are in considerable demand for use in connection with electric conductors. Heretofore they have been commonly made by bending a strip transversely to its length to bring its longitudinal edges together and wrapping spirally around the same another strip of paper. Better tubes can be made by taking a strip of paper or similar filament and winding it spirally around a mandrel in such manner that its coils will meet edge to edge, and in spirally winding outside of this strip a second strip and outside of the second strip a third strip, the lines of the joints on the several strips being staggered, or, in other words, arranged out of line. Each strip which is wound outside of the first will preferably be united with the one immediately underlying it by an adhesive substance.

The object of my improvement is principally to produce a machine which may be used for the making of these tubes.

The improvement consists in certain combinations of parts which I will particularly describe. After doing so, I will point out the novel features of the improvement in claims.

In the accompanying drawings, Figure 1 is a side view of a machine embodying my improvement and of certain means for driving the same. Fig. 2 is a longitudinal section of certain parts of the machine on a larger scale. Fig. 3 is a transverse vertical section of the machine taken at the plane of the dotted line $x x$ Fig. 1. Fig. 4 is a vertical section taken at the plane of the dotted line $y y$ Fig. 1. Fig. 5 is a view of some of the parts shown in Fig. 4 and representing them in a different position. Fig. 6 is also a view of some of the parts shown in Fig. 4, representing them in positions different from those occupied by them in Fig. 4. Fig. 7 is a top view of parts shown on Fig. 4. Fig. 8 is a vertical section taken at the plane of the dotted line $z z$ Fig. 1. Fig. 9 is an end view of the principal part of the machine, but this view does not include all the parts which might be seen in an end view.

Fig. 10 is a longitudinal section on an enlarged scale of a portion of the machine comprising devices for finishing the tube. Fig. 11 is a transverse vertical section taken at the plane of the dotted line $w w$, Fig. 10. Fig. 12 is a side view of a machine embodying the improvement, but modified in respect to certain parts. This view also includes certain means for driving the machine. Fig. 13 is a top view of a portion of the pasting apparatus of this machine. Fig. 14 is an end elevation of parts of this pasting apparatus. Fig. 15 is a central vertical section of a guide pulley over which a strip of paper passes to a mandrel on the machine. Fig. 16 is a vertical section taken at the line $v v$ Fig. 12. Fig. 17 is a top view of parts shown in Fig. 16. Figs. 18 and 19 are enlarged details. Fig. 20 is a plan view showing the path of the pasted strips to the mandrel.

Similar letters and numerals of reference designate corresponding parts in all the figures.

A designates the frame of the machine. It may be of any suitable construction and material.

B designates a mandrel fitted in a holder B' which is supported in bearings $b' b^2$ erected on the frame A of the machine. The holder is combined with means for rotating it which, as here shown, consist of a pulley b , and a belt b^3 surrounding such pulley and extending around a pulley c upon a counter shaft C. On the counter shaft C are fast and loose pulleys $c' c^2$, adapted to receive a belt whereby motion is at the proper times imparted to the shaft. The mandrel consists of a cylindric rod or shaft and it projects considerably beyond the bearing b' so as to extend between wheels $D' D^2 D^3$. Preferably the mandrel will be hollow and will have a current of hot air circulated through it for the purpose of drying a tube formed upon it. The wheels $D' D^2 D^3$ have their peripheries transversely curved on lines which are approximately concentric with the mandrel. Preferably the peripheries of these wheels will be roughened or faced with soft india rubber. As here shown, there are three of the wheels, and they are arranged equidistantly, as may be readily understood from Fig. 3. In Fig. 2 I have shown two of them in side view, so that all

their details might be seen. Of course the lower of these wheels would appear in perspective if drawn so as to show it in its true position.

- 5 The wheels $D' D^2 D^3$ are supported on non-rotary arbors or studs d , which are affixed to blocks d' fitting housings d^2 in brackets d^3 . The brackets d^3 are secured to a tubular shaft D , which is supported in bearings $d^4 d^5$, erected upon the frame A of the machine. This shaft as it rotates carries the wheels around the mandrel B . It is considerably larger than the mandrel, but the wheels $D' D^2 D^3$ are intended to be adjusted so that their peripheries will be close to the mandrel. To provide for this, screws d^6 are combined with the housings d^2 and blocks d' . This adjustment also enables the wheels to be adjusted suitably for operating in connection with different sized mandrels inserted in the holder B' .
- It is intended that strips $P' P^2 P^3$ of paper shall be wound around the mandrel and pressed toward the same by the wheels $D' D^2 D^3$. These wheels will also smooth down the strips after being wound and feed the tube P which is formed from them lengthwise through the shaft D . Motion is imparted to the shaft D by means of a pulley d^7 , which is affixed to it and receives a belt d^8 that passes around a pulley e^3 on the counter shaft C . The wheels $D' D^2 D^3$ have studs d^9 affixed to those sides which are the farthest from the brackets d^3 and these studs have affixed to them sprocket wheels d^{10} .
- Chains d^{11} engage with the wheels d^{10} and with corresponding sprocket wheels d^{12} , which are mounted loosely upon studs d^{13} , secured to the brackets d^3 . The wheels d^{12} are secured to worm wheels d^{14} , which are also loosely mounted upon the studs d^{13} . The sprocket wheels d^{12} therefore turn with the worm wheels d^{14} around the studs d^{13} . The worm wheels d^{14} engage with a worm d^{15} , which is formed on the exterior of the bearing d^4 of the tubular shaft D . As the shaft D carries the brackets d^3 around the axis of the mandrel B , the worm wheels d^{14} will be caused to revolve around the screwthread d^{15} , and, by revolving around the thread will be caused to rotate upon the studs d^{13} . Their rotary motion will be transmitted to the chain wheels d^{10} , by means of chains and thence to the wheels $D' D^2 D^3$. In this example of my improvement, the strips of paper $P' P^2$ are directed to the mandrel B by means of guide pulleys $p' p^2$, and the strip of paper P^3 is directed to the mandrel by a similar guide pulley. These guide pulleys may be supported in any suitable manner.
- A governor E maintains the strip P' under proper tension and regulates its feed. It comprises a bracket e in which is journaled a pulley e' and to which is fulcrumed a lever e^2 having pulleys $e^3 e^4$ journaled in its opposite ends on each side of the lever and provided with a weight e^5 which tends to oscillate the lever into a horizontal position. A belt e^6 ,

deriving power from any suitable source, passes under the pulley e^3 , over the pulley e^4 and under the pulley e' , after which it returns to the source of power. The belt is somewhat slack, and is kept sufficiently taut to transmit power by means of the weight e^5 with which the lever e^2 is provided. The object of combining the lever e^2 and its appurtenances with the belt e^6 and pulley e' is to maintain a uniform tension of the belt upon the pulley e' without making the tension too great. A pulley e^7 is journaled to one arm of the bracket e . A lever e^8 is fulcrumed between its ends to the bracket e and in the present instance above the journal of the pulley e' . One end is provided with a pulley e^9 . The strip of paper P' passes under the pulley e^7 and also under the pulley e^9 on its way to the guide pulley p' , whence it passes to the mandrel B . To the arm of the bracket in which the pulley e^7 is journaled, an arm e^{10} is pivoted. The inner end of the lever e^8 extends under the outer end of this arm e^{10} . The strip of paper P' becomes slack and allows the outer end of the lever e^8 to descend. The inner end of this lever will raise the arm e^{10} against the resistance of a spring e^{11} which at one end is fastened to the bracket e and at the other is fastened to the arm e^{10} so as to pull its end downward. The outer arm of the lever e^8 is intended to preponderate sufficiently over the inner arm so as to take up what slack will ordinarily exist in the strip P' . Affixed to the pulley e' is a roller e^{12} and above this roller e^{12} a similar roller e^{13} is journaled to the outer end of the arm e^{10} . These two rollers are in effect feed rollers, for they regulate the feed of the strip P' . Whenever slack occurs in the strip and the outer arm of the lever e^8 descends in consequence thereof, the roller e^{13} will be raised from the strip P' and after that the roller e^{12} will be unable to continue the feed of the strip. As soon as the slack of the strip P' shall have been taken up to the desired degree, the lever e^8 will be raised, so as to permit the roller e^{13} to descend again and force and hold the strip in contact with the roller e^{12} , whereupon the feeding of the strip will be resumed. This governor E prevents the strip P' from being wound so tightly about the mandrel as to cause it to cling.

It will of course be understood that the strips $P^2 P^3$ are wound outside the strip P' and are so disposed that the several coils of the three strips break joints with each other. Either one or both of the strips $P^2 P^3$ may be pasted upon its inner side. I have only shown a pasting apparatus in connection with the strip P^2 , but it is intended that a similar apparatus will be used in connection with the strip P^3 . In this example of my improvement, the pasting apparatus consists of a box F , preferably made of tinned iron, and containing a block w of nearly the same area as its interior and made of material sufficiently light to enable it to float on the top of a mass

of paste contained in the box. The block is provided with a bracket f in which is journaled a roller f' . Beneath this roller the block will be slotted so that the lower part of the roller may extend through it and contact with the paste. By contacting with the paste, it is intended to pick up paste and deposit it upon the under side of the strip P^2 . Of course this roller will be in the line which the strip takes after leaving its guide pulley p^2 .

The box F may be provided with a false bottom f^2 , which can be raised and lowered by means of a screw f^3 attached to it and a nut f^4 engaging with the screw and connected with the main bottom of the box. The false bottom will afford provision for raising the contents of the box for the purpose of elevating the pasting roller.

It will be advantageous to subject the tube to a scraping and smoothing operation for the purpose of finishing it. I provide for doing this by passing the tube through a rotary cylinder T furnished with scraping and smoothing device t , best illustrated in Figs. 10 and 11. The cylinder is supported by standards t' erected upon the top of the frame A of the machine. At one end it is journaled directly in one of the standards t' , but at the other end it has fitted to it a driving pulley t^2 and the hub of this pulley is journaled in the adjacent standard t' . This pulley need not be rigidly united with the cylinder T , but preferably will be clamped thereto so as to provide for a slipping of the pulley relatively to the cylinder, in the event of the scrapers or smoothers t encountering any obstruction. I have shown for this purpose a clamping plate t^{12} fastened to one side of the pulley t^2 by means of a screw t^{13} and having an arc-shaped end which bears against the circumference of the cylinder T . The driving pulley t^2 derives rotary motion through a belt t^3 which also passes around a pulley t^4 affixed to the shaft C . The scrapers or smoothers t are fitted in slots formed longitudinally in the cylinder T and they are pressed inwardly toward the center of the cylinder by means of springs t^{10} which in the present instance, are coiled around rods t^5 within cylinders t^6 , fastened to the cylinder T and extending radially from the circumference thereof. The cylinders t^6 are fitted in sockets t^7 , which are formed integral with the cylinder and slotted in the direction of their length, so as to have sections which may be drawn together with a clamping action. The cylinders may be adjusted longitudinally within said sockets and may be fastened therein by means of clamping screws t^8 , which operate in conjunction with rings t^9 surrounding the outer end portion of the sockets. At the outer ends the cylinders t^6 have caps t^{10} applied to them, and, as here shown, these caps are attached by means of screwthreads so as to be adjustable lengthwise of the cylinders. The springs t^4 coiled around the rods t^5 at one end bear against shoulders formed upon the rods and at the

other end against the caps t^{10} . The rods t^6 are shown as extending through the caps t^{10} , and at the outer extremities are provided with heads forming stops to prevent the knives t from moving too far toward the axis of the tube T .

Preferably there will be combined with the means which I have described for forming the tube devices whereby the tube may be cut transversely into pieces.

G designates a cutter, here shown as consisting of a rotary saw, which is intended to move in the direction of the length of the tube P , and as fast as this tube is moved, and to rotate simultaneously so that it may cut the tube at right angles to its axis. It is mounted upon a shaft g , which is journaled in an arm g' that extends from a sleeve g^2 . g^2 On the saw shaft is affixed a pulley g^{20} , which receives a belt g^{21} that passes around a pulley g^{22} , which is made very wide so that the belt may travel across it. The sleeve g^2 fits around a screw g^3 . It does not engage with the thread of the screw, but simply rests against the periphery of the thread. This screw is mounted on a shaft g^5 which is journaled in brackets $g^4 g^5 g^6$, erected upon the frame A . On one end of the shaft g^5 is a belt pulley g^7 which derives motion through a belt from a pulley g^8 , to the tubular shaft D carrying the wheels $D' D^2 D^3$. The sleeve g^2 is provided with a circumferential slot in which is pivoted by pins g^9 a finger g^{10} . This finger engages with the screwthread, and, while it remains in engagement with the screwthread, the screw will move the sleeve in the same direction that the tube P is propelled by the wheels $D' D^2 D^3$, and at the same speed. The finger g^{10} is raised beyond the peripheral line of the screwthread g^8 when the saw has moved a sufficient distance with the tube P to cut it through and is desired to return to the starting position. It is raised at the point where the face of the screwthread vanishes into the periphery of the shaft which is coincident with the outer circumference or periphery of the screwthread. The finger is held in engagement with the screwthread by means of a resilient bar g^{14} which extends in the direction of the length of the sleeve, above the finger. When the finger is raised by the ending of the screwthread groove, the bar g^{14} will yield, but as soon as the finger has passed beyond the end of the bar, the bar will drop to its normal position and its edge on a return movement of the finger will engage with a curved edge g^{35} of the finger g^{10} and thereby hold the finger in a raised position. After the raising of the finger, the saw will be moved in the reverse direction to the movement of the tube P for the purpose of returning to the starting position. This movement is accomplished by means of a weight g^{11} connected with a cord g^{12} passing around a pulley g^{13} journaled in the bracket g^4 and attached to the sleeve. During the return movement of the sleeve, the bar g^{14} will hold the finger g^{10} in a raised

position until it shall have been carried beyond that extremity of the bar g^{14} which is the nearest to the wheels $D' D^2 D^3$. By this time, the finger g^{19} will have been carried beneath a hooked arm g^{15} extending from a rock shaft g^{16} , and the hooked end of said arm g^{15} will retain the finger g^{19} in an elevated position. When it is desired that the saw shall again operate, the shaft g^{16} will be rocked to raise the arm g^{15} , whereupon the finger g^{19} will descend into the screwthread. The rock shaft is journaled in brackets g^{17} and is operated, in the present instance, by the tube P which is formed of the paper strips. The tube operates to do this by the contacting of its forward end with an arm g^{18} , which is mounted upon a rock shaft g^{19} that is journaled in a bracket g^{23} . One end of the rock shaft g^{19} extends near to the rock shaft g^{16} and this end has affixed to it an eccentric g^{24} . The rock shaft g^{16} has affixed to it an arm g^{25} that extends over the eccentric g^{24} . The rock shaft g^{19} is arranged at right angles to the rock shaft g^{16} , and, owing to this, the longitudinal movement of the tube P may impart motion to it, so as to cause its eccentric to oscillate the rock shaft g^{16} . It will be seen that whenever the forward end of the tube reaches the arm g^{18} , it will cause the hooked arm g^{15} to release the finger g^{19} , whereupon the sleeve g^3 will be caused to travel along the screw g^8 . After the forward end of the tube shall have been cut off and fallen or otherwise been delivered from the machine, the arm g^{18} will be released so that it may be returned by a spring g^{26} to its normal position. The bracket g^{23} , which carries the rock shaft g^{19} is connected to the frame A , so as to be capable of adjustment lengthwise of the latter into different positions. Obviously such an adjustment provides for cutting different lengths of tube in the machine.

Except while the saw G is being carried along with the tube through the agency of the screw g^8 , it is out of contact with the tube P . It is capable of a movement through the tube and away from it because the sleeve can oscillate around the screw. The sleeve has affixed to it a downwardly extending arm g^{27} which is provided with a weight g^{28} or its equivalent for forcing this arm toward the frame A . g^{29} is an inclined strip or cam along which the arm g^{27} travels when the sleeve is moved along the screw. By traveling along this incline or cam, the arm g^{27} is forced outward and consequently the saw G is forced through the tube P . When the sleeve returns to its normal position the arm g^{27} travels back along the inner side of the incline or cam g^{29} until it passes such incline or cam, whereupon it is ready to again co-operate with the incline or cam to force the saw through the tube.

The tube P forward of the saw G is supported in a trough H made of sheet metal and supported by arms h which are affixed to a rock shaft h' . This rock shaft h' is journaled

in one of the brackets g^{17} and in the bracket g^{23} and has affixed to it an arm h^2 having a cam-like outer extremity. The sleeve g^2 which surrounds the screw g^8 is provided with an arm g^3 , which contacts with the cam-like end of the arm h^2 just before the cutting of the tube by the saw has been completed, and rocks the shaft h' in such direction as to effect the withdrawal of the trough H from the contiguous part of the tube P . As this part of the tube has just previously been cut off by the saw, it will fall to the ground.

Turning now to the modification of the improvement shown in Figs. 12 to 17 inclusive, I will premise that it is identical with the machine already described excepting the difference in the mandrel B and in the manner in which the strips $P' P^2 P^3$ are wound around the mandrel B . The strips $P^2 P^3$ are pasted. The difference in these parts of the machine I will now describe. The mandrel B is here held stationary and has formed upon that part of its exterior which receives the strips $P' P^2 P^3$ a spiral thread of slight projection and pitched to correspond with the spiral line at which the strips $P' P^2 P^3$ are designed to be wound around the mandrel. $P' P^2 P^3$ designate strips similar to those already so designated. F' designates a paste box, here shown as of cylindric form and which may be made of brass or other suitable material. In it is arranged a weighted piston f^{10} , having a rod f^{11} passing upwardly through a guide in a cross-piece f^{12} attached to the top of the box F' . The paste box F' is arranged adjacent to the mandrel B and has extending from it in the direction of the mandrel a number of tubes f^{13} , which fit in sockets formed upon the box and are adjustable longitudinally within the sockets toward and from the center of the box. As the piston is not intended to descend below the uppermost tube, its motion will not be interfered with. The weight of the piston serves to force the paste out into the tubes. The sides of the tubes are provided with openings f^{14} , through which the paste may exude under control of slide valves f^{15} , which are capable of being moved lengthwise of the tubes by means of rods fitted to guides in the outer ends of the tubes and having handles beyond the tubes by which they may be adjusted. These valves may consist of pieces of soft rubber attached to metal rods and held to their seats in the tubes by means of springs f^{16} . Obviously by adjusting the valves so as to expose more of the openings f^{14} , the escape of the paste may be facilitated, and conversely, the escape of the paste may be reduced by moving the valves so as to cover more of the openings. Adjacent to the tubes are guide rollers $p^{10} p^{11}$. A pair of these guide rollers are adjacent to each of the tubes f^{13} , one of the pair being on each side of said tube. The rollers $p^{10} p^{11}$ are mounted loosely upon studs p^{12} extending horizontally from the paste box. The rollers are so located as to be substantially in line with the perforations f^{14} of the tubes

*f*¹³. Preferably these rollers will be severally constructed of two sections, 1, 2, each having a body and a flange and fitted to a piece of tube, 3, and fastened thereto by set screws, 4, as when thus made each will be adjustable for different widths of strips *P' P² P³*. The strip *P' P² P³* move in the direction indicated by the arrows in Fig. 14, passing from spools first over the rollers *p¹⁰*, thence under the tubes *f¹³* where the perforations *f¹⁴* are located, thence over the rollers *p¹¹* and from there around guides, *U*, to the mandrel *B*. Where it is not necessary that the strip *P'*, as well as the strips *p² p³* shall be pasted, the strip *P'* may pass directly from the spool to its guide *U*. The rollers *p¹⁰ p¹¹* and a tube *f¹³* will preferably, however, be provided for the strip *P'*, so that the latter may be pasted if desired. For each tube *f¹³* which is to be used to paste a strip, I preferably provide a brake, consisting, for example, of a lever *f¹⁷*, fulcrumed between its ends by pins *f¹⁸* to the paste box, having its operative end adapted to press against a strip passing around an opposite tube *f¹³*, and provided at the other end with some device as, for instance a weight *f¹⁹* for impelling the operative end against the strip. The rollers *p¹⁰ p¹¹* and the openings *f¹⁴* of the tubes *f¹³* are located in different planes, or, in other words, at different distances from the paste box, so that the strips *P' P² P³* in passing around them shall not interfere.

I will now explain the construction of the guides *U*. There will be one for each strip *P' P² P³*. Each comprises a collar *u* mounted upon a stud *u'* extending from the bracket or bearing *b'* under the mandrel *B*. Each collar *u* is constructed so that it may be clamped in position on the stud *u'*, and, owing to this, provision is afforded for adjusting the several collars into different positions on said stud. From each collar an arm *u²* extends horizontally at right angles to the length of the stud *u'*. The paste box *F'* is farther in the background than the mandrel *B* and the arms *u²* extend toward the plane or line of the paste box, or rearward in Fig. 16. At its extremity, each rod *u²* has combined with it a clamp collar *u³*, having two clamping portions, one of which fits the corresponding rod *u²* and the other of which receives within it a rod *u⁴*, that extends parallel with the stud *u'*. The collar *u³* is adjustable along the adjacent rod *u²* toward and from the stud *u'* and the corresponding rod *u⁴* is adjustable in the direction of its length on the stud *u'* within the collar *u³*. In the outer extremity of each rod *u⁴* is a trough-shaped guide *u⁵*, through which a strip *P' P²* or *P³* passes on its way to the mandrel *B*. The several strips are directed by the guides *u⁵* properly to the mandrel.

What I claim as my invention, and desire to secure by Letters Patent, is—

1. In a machine for winding strips or filaments, the combination of a paste box, tubes

extending therefrom, openings in said tubes, 70 guide pulleys for directing strips or filaments across the openings of said tubes and a mandrel around which said strips or filaments may be wound, substantially as specified.

2. In a machine for winding strips or filaments, the combination of a paste box, tubes 75 extending therefrom, openings in said tubes, valves for controlling the openings, guide pulleys for directing strips or filaments across the openings of said tubes and a mandrel around which said strips or filaments may be wound, substantially as specified. 80

3. In a machine for winding strips or filaments, the combination of a paste box, tubes extending therefrom and provided with openings, guide rollers adjacent to said openings, guides, *U*, and a mandrel around which said strips or filaments may be wound, substantially as specified. 85

4. In a machine for winding strips or filaments, the combination of a mandrel having a screwthread of slight projection upon its 90 exterior, and a number of wheels revolving around the axis of said mandrel and rotating upon their own axes, substantially as specified.

5. In a machine for making a tube by winding strips or filaments, the combination with 95 a mandrel wheels revolving around the axis of the same and rotating upon their own axes and means for adjusting the same toward and from the mandrel of a scraping or smoothing device consisting of a cylinder 100 furnished with scrapers or smoothers adjustable toward and from the axial line of said cylinder, substantially as specified.

6. In a machine for making a tube by winding strips or filaments, the combination with 105 a mandrel wheels revolving around the axis of the same and rotating upon their own axes, and means for adjusting the same toward and from the mandrel of a scraping or smoothing device consisting of a cylinder furnished with scrapers or smoothers adjustable toward and from the axial line of said cylinder and springs for regulating the pressure of said scrapers or smoothers, substantially as specified. 110 115

7. In a machine for making a tube by winding strips or filaments, the combination with 120 a mandrel wheels revolving around the axis of the same and rotating upon their own axes, and means for adjusting the same relatively to the mandrel of a scraping or smoothing device consisting of a cylinder furnished with scrapers or smoothers adjustable toward and from the axial line of said cylinder, springs for regulating the pressure of said scrapers 125 or smoothers and means for adjusting the tension of the springs, substantially as specified.

8. In a machine for making a tube by winding strips or filaments, the combination with 130 a mandrel wheels revolving around the axis of the same and rotating upon their own axes, and means for adjusting the wheels relatively to the mandrel of a scraping or smoothing de-

vice consisting of a cylinder furnished with scrapers or smoothers adjustable toward and from the axial line of said cylinder and stops for limiting the inward movement of the 5 scrapers or smoothers.

9. In a machine for making a tube by winding strips or filaments, the combination with a mandrel wheels revolving around the axis of the same and rotating upon their own axes, 10 and means for adjusting the wheels relatively to the mandrel of a scraping or smoothing device consisting of a cylinder furnished with scrapers or smoothers adjustable toward and from the axial line of said cylinder and a 15 driving pulley having a flexible connection with said cylinder whereby a slip may occur between said pulley and said cylinder, substantially as specified.

10. The combination, with mechanism for 20 winding strips or filaments, of a cutter, a support for the cutter movable in the direction of the length of a tube formed by winding said strips or filaments, a screw for moving the support in the direction of the length of the 25 said tube a movable finger carried by the support for engaging the screw and a cam or incline for moving said support transversely to the length of the tube, substantially as specified.

30 11. The combination, with mechanism for winding strips or filaments, of a cutter, a sleeve g^2 by which said cutter is supported, a screw g^3 around which said sleeve extends, and a finger g^{10} pivoted to said sleeve and constructed to engage with the screw, substantially as specified.

12. The combination, with mechanism for 40 winding strips or filaments, of a cutter, a sleeve g^2 by which said cutter is supported, a screw g^3 around which said sleeve extends, a finger g^{10} pivoted to said sleeve and constructed to engage with the screw, and a resilient bar g^{14} for holding the finger in engagement with the screw until said finger passes beyond the 45 end of the screw and for subsequently holding the finger in an elevated position so as to permit of the return movement of the sleeve, substantially as specified.

13. The combination, with mechanism for 50 winding strips or filaments, of a cutter, a sleeve g^2 by which said cutter is supported, a screw g^3 around which said sleeve extends, a finger g^{10} pivoted to said sleeve and constructed to engage with the screw, a resilient bar g^{14} for holding the finger in engagement with the screw until said finger passes beyond the 55 end of the screw and for subsequently holding the finger in an elevated position so as to permit of the return movement of the sleeve, and a weight or its equivalent for returning the sleeve, substantially as specified.

14. The combination, with mechanism for 60 winding strips or filaments, of a cutter, a support for the cutter movable in the direction of the length of a tube formed by winding said strips or filaments, a screw for moving 65 said support in the same direction as said tube,

a weight or its equivalent for returning the said support to its normal position, a finger whereby the support may be engaged with 70 and disengaged from the screw and mechanism, substantially such as described, operated by said tube for controlling said finger, substantially as specified.

15. The combination, with mechanism for 75 winding strips or filaments, of a cutter, a sleeve g^2 by which said cutter is supported, a screw g^3 around which said sleeve extends, a finger g^{10} pivoted to said sleeve and constructed to engage with the screw, a resilient bar g^{14} for holding the finger in engagement with the screw until said finger passes beyond the end of the screw and for subsequently holding the finger in an elevated position so as to permit of the return movement of the sleeve, 85 a rock shaft g^{16} , a hooked arm g^{15} for engaging with the finger after it shall have passed beyond the bar g^{14} in the return movement of the sleeve, an arm g^{25} affixed to said rock shaft g^{16} , a rock shaft g^{19} arranged transversely 90 to the rock shaft g^{16} , an eccentric on said rock shaft g^{19} for operating upon the arm g^{25} and an arm g^{18} which is operated by the said tube that is formed by winding the strips or filaments, substantially as specified.

95 16. The combination, with mechanism for winding strips or filaments, of a cutter, a support for said cutter made in the form of a sleeve, a screw for moving this support in the same direction as the tube, a stationary cam or incline for rocking the sleeve so as to move the cutter transversely to the tube, a finger for engaging and disengaging the sleeve with the screw, a weight or its equivalent for returning the sleeve to its normal position and mechanism for controlling said finger, substantially as specified.

17. The combination, with mechanism for winding strips or filaments, of a cutter for severing the tube, and movable in the direction of the length of the tube a trough-shaped support for the forward end of the tube, a rock shaft for sustaining this trough-shaped support and mechanism for operating said rock shaft so as to cause it to remove the trough-shaped support from beneath the adjacent portion of the tube, substantially as specified.

110 18. The combination, with mechanism for winding strips or filaments, of a cutter, a support for the cutter movable in the same direction as the tube, a trough-shaped support for the forward portion of the tube and a rock shaft sustaining said support and having an arm that has a cam-like extremity with which it acts an arm extending from the cutter support, substantially as specified.

115 In testimony whereof I have signed my name to this specification in the presence of two subscribing witnesses.

REINHART SPENGLER.
